US00D797283S

(12) **United States Design Patent** (10) **Patent No.:** **US D797,283 S**
(45) **Date of Patent:** **** Sep. 12, 2017**

(54) **ENDOSCOPE CONNECTOR**

(71) Applicant: **FUJIFILM Corporation**, Tokyo (JP)

(72) Inventors: **Ryosuke Ogura**, Kanagawa (JP); **Koji Yoshida**, Kanagawa (JP)

(73) Assignee: **FUJIFILM Corporation**, Tokyo (JP)

(**) Term: **15 Years**

(21) Appl. No.: **29/530,191**

(22) Filed: **Jun. 15, 2015**

(30) **Foreign Application Priority Data**

Dec. 16, 2014 (JP) 2014-028034

(51) **LOC (10) Cl.** **24-02**

(52) **U.S. Cl.**

USPC **D24/138**

(58) **Field of Classification Search**

(57) **CLAIM**

The ornamental design for an endoscope connector, as shown and described.

DESCRIPTION

FIG. 1 is a top, front and left side perspective view of an endoscope connector showing my new design;

FIG. 2 is a bottom, front and left side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof;

FIG. 8 is a right side elevational view thereof; and,

FIG. 9 is a top, front and right side perspective view thereof in a manner of use.

The broken line portions of the endoscope connector throughout the drawings are shown to illustrate environment only and form no part of the claimed design.

1 Claim, 8 Drawing Sheets
